ROSE BROTHERS (GAINSBOROUGH) LIMITED, OF GAINSBOROUGH, ENGLAND, A
BRITISH COMPANY

MACHINE FOR WRAPPING CARAMELS AND LIKE ARTICLES

Application filed March 8, 1929, Serial No. 345,537, and in Great Britain March 22, 1928.

This invention is concerned with wrapping machines of the type designed to operate on a continuous bar of confectionery stock and provided with means for severing successive portions in the length of the bar to form individual caramels, and with means for feeding said caramels to a rotatable mould-wheel or equivalent intermittently-operable wrapping mechanism. In a machine of this type, there is also a stock-feeding device (e. g. a series of rollers) which operates intermittently to feed the leading end of the bar of stock to a cutting station where the cutting of separate caramels from the bar is effected.

Hitherto, in machines of the above type, the stock-feeding device and the mould-wheel have been arranged to make their intermittent movements simultaneously, and the intermediate operations of cutting the bar and feeding the caramel into the mould-wheel have been performed during the idle intervals between the intermittent movements aforesaid, that is to say, while both the stock-feeding device and the mould-wheel are at rest. On account of the time intervals necessary for the effective performance of the intermediate operations—time which is lost so far as the output of the machine is concerned—it has been impossible efficiently to run a machine, operating in the above manner, at other than comparatively slow speeds.

According to the present invention, a wrapping machine of the type referred to is arranged to operate in such manner that the intermittent movements of the stock-feeding device are out of phase with the correlated intermittent movements of the mould-wheel or equivalent wrapping mechanism.

With a machine operating according to the invention, the mould-wheel can be arranged to make its intermittent movements during the first stage at which the intermediate operations are in progress so that the intervals required for the performance of said operations do not, to the same extent as before, represent lost time. The advantage of the invention can be considered from another angle. The intermediate oper-

ations have to be performed in the intervals between the cessation of movement of the stock-feeding device and the commencement of movement away from the charging station of the pocket which is to receive the caramel. By throwing the stock-feeding device out of phase with the mould-wheel, the intervals aforesaid may be increased for the same speed of the machine, and, conversely, the machine may be run at a higher speed and give the same intervals for the intermediate operations as obtain in a slower-speed machine with the mould-wheel and stock-feeder operating simultaneously.

The mould-wheel has to remain at rest for a definite period while the caramel is actually being forced, with its wrapper, into the wheel pocket. This and other considerations limit the extent to which the operations of the mould-wheel can be displaced in relation to those of the stock-feeder. In practice, it is found convenient to have the mould-wheel make its intermittent movements at times midway or thereabouts between consecutive movements of the stock-feeding device.

According to a feature of the invention, the mould-wheel, and the stock-feeding device are actuated from one and the same driving-shaft by operating elements between which there is a phase displacement in the region of 200° . The mould-wheel and the stock-feeder may be operated respectively by two Geneva stop mechanisms whereof the star-wheels are arranged for rotation independently of each other about the same axis under the influence of driving-pins or the like carried by arms radiating from the same driving-shaft.

A caramel-wrapping machine embodying the invention will now be described by way of example with reference to the accompanying drawings in which—

Figure 1 is a plan view showing those parts of the machine with which the invention is concerned;

Figure 2 is an elevation corresponding to Figure 1 and

Figure 3 is an end view showing the phase displacement between the driving-members

for the stock-feeding rollers and the mould-wheel.

Like reference numerals indicate like parts in the three figures.

5 The machine is of the kind in which the cutting of separate caramels from the bar of stock is effected at a point spaced away from the path of the pusher which operates in conjunction with the mould-wheel, and transfer-
10 mechanism is provided to convey the caramels one at a time from the cutting station into the path of the pusher.

15 Referring to Figures 1 and 2, the mould-wheel 10 of usual type is mounted for inter-
mittent rotational movement about a hori-
zontal axis, and is provided with six caramel-
receiving pockets or mould-boxes (not
shown) arranged around the periphery of
the wheel at equally spaced intervals. The
20 bar of stock 11 is fed along a horizontal
guide-way 12 by means of feed-rollers 13, 14,
located one above the other, and thence over a
bridge-piece 15 and between rollers 16, 17,
which are arranged, side by side, to feed the
25 forward end of the bar downwardly. The
end of the bar is received in one of four chan-
nel-shaped holders 18 formed in a ring-mem-
ber 19. It will be seen from Figure 1 that
the position to which the leading end of the
30 bar is fed by the rollers 16, 17, is offset later-
ally from the plane of rotation of the mould-
wheel 10. This position constitutes the cut-
ting station at which a knife 20, operating
in a horizontal plane, severs separate cara-
mels from the bar.

35 The ring 19 has imparted to it (e. g. by a
Geneva stop mechanism, the star-wheel of
which is indicated at 21) a step-by-step rota-
tional movement such that at each step, the
40 ring is rotated through a quarter of a revolu-
tion. The ring 19 is so positioned that
during each of the intervals at which it is at
rest, one of the channel-holders 18 will be lo-
cated at the cutting station aforesaid, (i. e.
45 ready to receive the leading end of the bar
from the feed rollers 16, 17) while an adj-
acent channel will be in a position (herein-
after referred to as the "wheel-charging sta-
50 tion") opposite to the mould-wheel 10. At
each movement of partial rotation of the ring
19, a caramel is moved through a quadrant
path from the cutting station to the wheel-
charging station, at which a reciprocating
55 pusher 22 operates to force the caramel from
the ring channel 18 through a guide 23 and
into a receiving pocket of the mould-wheel.
Prior to each forward stroke of the pusher, a
60 wrapper 24, cut from a continuous web, is
located between the mouth of the guide 23
and the periphery of the mould-wheel, so that
as the caramel is pushed into the wheel, a
65 wrapper-sheet is carried with it and partially
folded about it. The folding operations are
completed in known manner during the con-

tinued step-by-step advance of the mould-
wheel.

70 The operating mechanism for the mould-
wheel and the stock-feeding rollers will now
be described. The mould-wheel is carried on
a spindle 25 which is rotatable in suitable
bearings, and at one end has secured to it the
star-wheel 26 of a Geneva stop mechanism
whereof the driving-member, constituted by
75 a roller 27, is carried on an arm 23 secured
to the end of a continuously-running driving-
shaft 29. As shown in Figure 3, the star-
wheel 26 has six radial slots (i. e. correspond-
ing in number to the pockets of the mould-
wheel 10) so that each time the star-wheel is
80 operated, the mould-wheel is carried through
one-sixth of a revolution and a fresh pocket
is brought up to the wheel-charging station.
The stock-feeding rollers are driven from the
85 same main shaft 29 by means of a second
Geneva stop mechanism comprising a star-
wheel 30 which is arranged face-to-face with
the wheel 26 and rotatable about the same
axis as the latter, and is operated by a roller
90 31 mounted on an arm 32 carried by the shaft
29. The star-wheel 30 is secured to a sleeve
95 33 which surrounds the spindle 25 and is ro-
tatable independently thereof. By means of
two sets of bevel-wheels 34, 35, the sleeve 33
is arranged to transmit rotational movement
to the feed-roller 13 which in turn rotates the
100 other rollers 14, 16 and 17 through a train
of intermeshing gears 36—40 (Figure 2).
The star-wheel 30 has six slots so that for
each actuation by the roller 31, the wheel is
105 rotated through one-sixth of a revolution.

110 It will be seen from Figure 3 that the arms
28, 32, are so relatively positioned that on
the rotation of the driving-shaft 29, there is
a phase difference of 200° between the opera-
tions of the mould-wheel and those of the
115 stock-feeding rollers. In the position of the
parts shown in Figures 2 and 3, the roller 31
is in engagement with the star-wheel 30 and
the stock-feeding rollers are at the middle of
a feeding movement. On further rotation of
120 the driving-shaft 29, the roller 27 comes into
operation to rotate the star-wheel 26 and con-
sequently the mould-wheel, and this move-
ment takes place after the knife 20 has oper-
ated and during the partial rotation of the
ring 19 to bring the caramel into register
with the mould-wheel. With the above ar-
rangement, as already explained, the speed
125 of the machine can be considerably increased.
An important advantage of the invention is
that a relatively longer time can be obtained
for the actual pushing of the caramel into
the mould-wheel.

I claim:

1. In a wrapping machine of the type de-
scribed operable on a continuous bar of con-
fectionery stock, the combination of an inter-
mittently operable wrapping mechanism, a

- stock feeding device operable intermittently to feed the leading end of the bar of stock to a cutting station, means operable at the aforesaid station to sever successive portions in the length of the bar to form individual caramels, means for feeding said caramels to the aforesaid wrapping mechanism, and means for operating the wrapping mechanism and the stock feeding device in such manner that their respective intermittent movements are co-related but out of phase with each other.
2. In a wrapping machine of the type described operable on a continuous bar of confectionery stock, the combination of an intermittently operable wrapping mechanism, a stock feeding device operable intermittently to feed the leading end of the bar of stock to a cutting station, means operable at the aforesaid station to sever successive portions in the length of the bar to form individual caramels, means for feeding said caramels to the aforesaid wrapping mechanism, and means for operating the wrapping mechanism and the stock feeding device in such manner that the intermittent movements of the former will take place at times about mid-way between consecutive movements of the stock feeding device.
3. In a wrapping machine of the type described operable on a continuous bar of confectionery stock, the combination of an intermittently operable wrapping mechanism, a stock feeding device operable intermittently to feed the leading end of the bar of stock to a cutting station, means operable at the aforesaid station to sever successive portions in the length of the bar to form individual caramels, means for feeding said caramels to the aforesaid wrapping mechanism, a continuously rotating shaft, operating elements arranged on said shaft to operate the wrapping mechanism and the stock feeding device, said operating elements being so relatively positioned that between them there is a phase displacement in the region of 200° .
4. In a wrapping machine of the type described operable on a continuous bar of confectionery stock, the combination of an intermittently operable wrapping mechanism, a stock feeding device operable intermittently to feed the leading end of the bar of stock to a cutting station, means operable at the aforesaid station to sever successive portions in the length of the bar to form individual caramels, means for feeding said caramels to the aforesaid wrapping mechanism, a continuously running shaft, and means for operating the wrapping mechanism and the stock feeding device from said shaft comprising two Geneva stop mechanisms having star wheels arranged for rotation independently of each other about the same axis under the influence of driving elements carried by the aforesaid shaft at positions thereon between which there is an angular displacement.
5. In a wrapping machine of the type described operable on a continuous bar of confectionery stock the combination of an intermittently rotatable mould-wheel, a reciprocating pusher for feeding caramels one at a time into the mould-wheel, mechanism for feeding a bar of stock up to a station offset laterally from the path of the pusher, means for cutting separate caramels from the stock at said station, transfer mechanism to convey the caramels one at a time from the cutting station into the path of the pusher, and means for operating the mould-wheel and the stock feeding mechanism to make their respective intermittent movements at times which are out of phase with each other.
6. In a wrapping machine of the type described operable on a continuous bar of confectionery stock the combination of an intermittently rotatable mould-wheel, a reciprocating pusher for feeding caramels one at a time into the mould-wheel, mechanism for feeding a bar of stock up to a station offset laterally from the path of the pusher, means for cutting separate caramels from the stock at said station, transfer mechanism to convey the caramels one at a time from the cutting station into the path of the pusher, a continuously running driving shaft, two Geneva stop mechanisms comprising star wheels rotatable independently of each other about the same axis, one operatively connected to the mould-wheel and the other to the stock feeding mechanism, and two wheel-operating arms mounted on the aforesaid continuously running shaft to co-operate with the two star wheels respectively, said operating arms being spaced apart angularly on the shaft aforesaid.
- In testimony whereof I affix my signature.
- ALFRED GERMAN ROSE.
